UNITED STATES PATENT OFFICE.

RAYMOND E. DODGE, OF NEW HAVEN, CONNECTICUT.

IRONING MACHINE.

1,091,027.

Specification of Letters Patent.

Patented Dec. 9, 1913.

Application filed June 26, 1913. Serial No. 776,661.

To all whom it may concern:

Be it known that R. RAYMOND E. DODGE, a citizen of the United States, residing at New Haven, in the county of New Haven and State of Connecticut, have invented a new and useful Improvement in Ironing-Machines; and I do hereby declare the following, when taken in connection with the accompanying drawings and the characters 10 of reference marked thereon, to be a full, clear, and exact description of the same, and which said drawings constitute part of this application, and represent, in—

Figure 1 a top or plan view of an ironing machine constructed in accordance with my invention. Fig. 2 a view partly in side elevation, and partly in vertical section of the same. Fig. 3 a front view. Fig. 4 a sectional view on the line *a—b* of Fig. 2, 20 looking in the direction of the arrow *c*. Fig. 5 a view on the same line looking in the direction of the arrow *d*. Fig. 6 a broken detail view showing the tripping mechanism in the operating position.

This invention relates to an improvement 25 in ironing machines, and particularly to machines for ironing flat work, such as corsets, shirts, &c. In the ironing of such articles it is necessary to shift the goods at opposite ends of the stroke of the iron.

The object of this invention is to provide means for adjusting the length of the stroke, and instead of lifting the iron I automatically drop the table at the end of each 30 stroke.

The invention consists in certain details of construction and combinations of parts as will be hereinafter described and particularly recited in the claims.

In carrying out my invention I employ a frame including a front wall 2 upon which the table 3 is vertically adjustable. The upper end of the front wall is formed with a vertically arranged slot 4 for the clearance 40 of the tail piece 5 which carries rollers 6 and 7 bearing against the rear face of the wall 2 which at its upper end is made somewhat thicker than the lower portion. The table 3 has a web which also carries 45 rollers 9 bearing against the outer face of the wall 2 by which the table is held in a horizontal position and yet free to move vertically. Preferably a pocket 10 will be formed in the thickened portion 11 at the 50 upper edge of the table to receive a spring 12 bearing upon the tail 5, and in effect sub-

stantially counterbalancing the table, or at least assisting in raising it but not interfering with its depression. This table is raised and lowered by means of a sliding cam 13 having bearings 14 in the frame and bearing upon an anti-friction roller 15 mounted in the tail 5. This cam is moved from one side to the other by means of an arm 16 entering a slot 17 in the cam, and this arm 16 is fixed to a sleeve 18 on a vertically arranged shaft 19 which at its lower end carries a belt-shifting lever 20 connected with a belt-shifting bar 21 by which the belts 22 and 23 are alternately shifting onto the fixed pulley 24 from idlers 25 and 26.

The iron 27 is of usual form mounted between downwardly extending ears 28 in a horizontal reciprocating arm 29. The ears are slotted for the reception of trunnions 30 on the iron, and between the outer end of the reciprocating arm and the iron is a spring 31 tending to force the iron toward the table and allowing for variation in thickness of the work or a slight movement 35 of the table. The outer end of the arm 29 is also provided with an upwardly extending finger 32 carrying rollers 33 which ride in slots 34 formed in the guide-frame 35 which is adjustably secured to the upper 40 end of the cross-plate 36 of the frame. This arm 29 is provided in its under face with a rack 37 meshing with a gear 38 driven by a pinion 39 on the driving shaft 45 driven by the fixed pulley 24 so that the 45 arm is given a reciprocating movement back and forth over the table 3. The arm 29 passes through U-shaped bearing blocks 41 mounted on trunnions 43, 44, projecting inward from bearings 45, 46, formed integral 50 with the side walls 47, 48, of the frame. This provides for a very slight tipping of the reciprocating arm as may become necessary in adjusting the guide-frame 35.

To turn the shaft 19 it is provided at its 55 upper end with a lever 49 which projects into the path of pins 50, 51, mounted in a rocker-arm 52 which is also provided at its opposite ends with pins 53, 54. This rocker-arm is mounted on and fixed to the sleeve 59. The upper face of the slide arm 29 is formed with an undercut longitudinal groove 65 to receive stop-blocks 56, 57, which are adjustable in the groove and may be locked by wrench nuts 58, 59. Carried 60 by these blocks are inwardly projecting tripping pieces 60 and 61, provided with notches

62, 63, to engage respectively with the pins 53, 54, the blocks also engaging with the pins 50 and 51 on the rocker-arm 52.

In Figs. 1 and 2 of the drawings, the iron 5 is shown as nearly at the limit of its rearward movement, and at this point the end 10 of the block 60 is about to engage with the pin 50 to turn the rocker-arm so as to operate the cam 13 to depress the table 3. After 15 the table is started to be depressed the pin 50 engages with the lever 49 and turns the shaft 19 so as to shift the belts. The entrance of the pin 53 into the notch 62 insures the return movement of the rocker-arm into the normal position. As soon as 20 the belts are shifted, the arm 29 starts on its outward movement, and this outward movement turns the rocker-arm so as to move the cam 13 to raise the table, and leaves it in 25 that position until the tripping-piece 61 engages with the pin 51, again dropping the table and shifting the belts in the manner before described. It will be seen that the 30 table is depressed at the end of each stroke of the iron, giving time at the end of each stroke to shift the work on the table. By adjusting the guide-frame vertically, I provide for work of different thickness and different pressures of the iron upon the 35 work, and by adjusting the tripping-pieces 60 and 61 on the arm the length of the stroke may be adjusted to any length desired.

I claim:

1. In an ironing machine, the combination with the frame, of a vertically movable table connected therewith, an iron adapted to be moved back and forth over 40 said table, automatic means operating to move the iron back and forth, and lower and raise the table at the end of each stroke of the iron.

2. In an ironing machine, the combination with the frame, of a vertically movable table connected therewith, a guide-frame above the table, a longitudinally movable iron above said table and guided by said guide-frame, means operating to move the iron, and lower and raise the table at 50 the end of each stroke of the iron.

3. In an ironing machine, the combination with the frame, of a vertically mov-

able table connected therewith, an iron longitudinally movable above said table, adjustable stops for regulating the length of 55 the stroke of said iron, and means operating to move the iron and lower and raise the table at the end of each stroke.

4. In an ironing machine, the combination with the frame, of a vertically movable table connected therewith, a longitudinally movable arm above said table, an iron connected with the outer end of said arm, a rigid guide-frame for guiding the outer end of said arm, and means operating 60 to move said arm back and forth over said table, and lower and raise the table at the end of each stroke of the iron.

5. In an ironing machine, the combination with a frame, of a vertically movable 70 table connected therewith, a longitudinally movable arm, an iron connected with the outer end of said arm, said arm formed in its under face with a rack, a gear for engagement with said arm, means for moving 75 the gear in opposite directions whereby the arm is moved back and forth, a sliding cam adapted to lower and raise said table, connections between the arm and cam whereby the table is lowered and raised at the end of 80 each stroke of the arm.

6. In an ironing machine, the combination with a frame formed in its front wall with a slot, of a table provided with a tail extending through said slot, bearings on 85 said table and tail for engagement with opposite walls of the frame, a spring between said frame and table, a cam engaging with said tail, a longitudinally movable sliding arm above said table, an iron connected 90 with the outer end of said arm, a guide frame guiding the said arm, means for moving said arm back and forth, and means operated by said arm for reversing the movement of the arm and for lowering and 95 raising the table at the end of each stroke.

In testimony whereof, I have signed this specification in the presence of two subscribing witnesses.

RAYMOND E. DODGE.
